UNITED STATES PATENT OFFICE

JULIUS A. SCHWANTES, OF WAUWATOSA, WISCONSIN, ASSIGNOR TO COLGATE-PALM-
OLIVE-PEET COMPANY, OF CHICAGO, ILLINOIS, A CORPORATION OF DELAWARE

SOAP MANUFACTURE

Application filed March 13, 1931. Serial No. 522,320.

The invention relates to soap manufacture.

Heretofore in the manufacture of soap it has been customary to deliver the soap from the plodder in long bars, several of which are allowed to accumulate and then an operator takes these long bars to a soap cutting apparatus in which they are cut up into a number of small cakes and another operator sees that these cakes are removed from the cutting apparatus and delivered to a conveyor by which they are taken to finishing apparatus and then to the labelling and packing mechanism. As an example of a cutting apparatus that has been heretofore used requiring two operators, reference may be had to my prior U. S. Patent No. 1,760,087, filed May 27, 1930. Furthermore, in connection with any of the cutting mechanisms that have been heretofore used, there is always a certain amount of waste from each of the long bars after the cutting operation that has to be taken care of. One object of the present invention is to improve that part of the process of soap manufacture where the soap cakes are formed by forming the soap into cakes directly at or as it is discharged from the plodder so that the labor heretofore necessary in handling and cutting the long bars of soap into cakes is eliminated.

A further object of the invention is to provide an apparatus by which the soap cakes may be formed as a continuous process and by which the soap cakes may be polished or finished and completely ready for packaging without any intermediate handling by an operator after the cakes are formed.

The invention further consists in the several features of the method and apparatus as hereafter described and more particularly defined by claims at the conclusion hereof.

In the drawings, Fig. 1 is a side elevation view of an apparatus embodying the invention and for use in connection with the method, parts being broken away and parts being shown in section;

Fig. 2 is a plan view of the structure shown in Fig. 1, parts being broken away and parts being shown in section;

Fig. 3 is a detail sectional view taken on the line 3-3 of Fig. 1;

Fig. 4 is a detail vertical sectional view taken on the line 4—4 of Fig. 3;

Fig. 5 is a detail sectional view taken on the line 5—5 of Fig. 1;

Fig. 6 is a detail sectional view taken on line 6-6 of Fig. 2;

Fig. 7 is a detail sectional view taken on line 7-7 of Fig. 2;

Fig. 9 is a detail sectional view taken on the broken line 9--9 of Fig. 8.

Referring to Fig. 4, the numeral 10 designates the mouth or nozzle of any suitable plodder mechanism and into which nozzle the soap is forced by the usual feed screw or screws of the plodder under pressure. As the soap is forced through this nozzle 10 it is acted upon by a pair of pusher members 11 mounted on oscillatory shafts 12 moved as hereinafter described. The pusher members 11 are for the purpose of quickly forcing the soap ahead when the die drum or member 15 is at rest and when receding stop the movement of the soap at the outlet at the time the member 15 is in motion. The front end of the nozzle 10 is provided with a jacket space 13 for the circulation of a suitable heating medium therethrough when desired. A nozzle

zle member 14 is adapted to fit within the recessed front end of the nozzle 14, and its front face 14 is curved to conform to the curvature of a mold carrying member 15 which is provided with a plurality of radially disposed cake mold cavities 16. The member 14 is yieldingly held against the member 15 by a series of springs 15' mounted in recesses 16' and engaging lugs 17' on the member 14, one of the springs being shown in Fig. 9. These cavities are preferably open at the back but are backed during a portion of the travel of member 15 by a relatively fixed backing plate 17. When any one of the mold cavities 16 is presented to the mouth of the plodder as shown in Fig. 4, it will be seen that the soap S will be discharged directly from said mouth into said cavity and as the member 15 moves to its next position, the soap in the cavity is cut off from the soap in the nozzle 10 and the

cake C is thereafter subjected to certain finishing operations as hereinafter described. The mold carrying member 15 may be operated by hand or by power, but preferably by power. From the above it will be noted that by presenting the soap mold directly at the mouth of the plodder and charging this mold by soap forced into the same that the soap is formed directly into a cake at this point and that by this method of forming the cake the usual cutting of the soap into cakes from long bars and the services of operators to accomplish the same have been eliminated. The advantages derived from practicing this method may of course be obtained by apparatus other than that shown and described herein but the apparatus herein shown constitutes a preferred form of apparatus for carrying out the method expeditiously and continuously and will now be described in detail.

Referring to Figs. 1, 2 and 3, the numeral 20 designates generally the main framework of the machine supported on suitable legs or uprights 21; and 22 is the main power take off shaft journalled in bearings 23 suitably supported by rods 24 below the main frame and carrying sprockets 25, 26 and 27, see Fig. 5. The sprocket 25 is adapted to be connected by a chain 28 to any suitable source of power. Sprocket 26 is connected by a chain 29 to a sprocket 30 on one of the parts of a transmission shaft 31 and sprocket 27 is connected by a chain 32 to a sprocket 33 on a shaft 34. The shaft 31 is connected by a double chain and sprocket drive including sprockets 35 on said shaft, chains 36, and sprockets 37 on a shaft 38 to said last named shaft. A Geneva toothed gearing connects the shaft 38 with a shaft 39 carrying a gear 40 meshing with a gear 41 mounted on a shaft 42 carrying the mold carrying member or carrier 15. The shaft 31 is journalled in suitable bearing brackets 43 mounted on the main frame, the shafts 38 and 39 are journalled in the spaced brackets 44 and 45 while the shaft 42 is journalled in bearings 46 mounted in a housing 47 suitably secured to the brackets 44 and 45. The Geneva stop gearing includes the Geneva toothed wheel 48 on the shaft 39 having the tooth slots 49 engaged by the pin or roller 50 on an arm 51 secured to the shaft 38 and having lock recesses 52 cooperating with the lock disk 53 on the shaft 39 whereby as the shaft 38 is rotated continuously, the shaft 39 is given an intermittent or step by step rotation which is transmitted through the gears 40 and 41 to the shaft 42.

The member 15 is in the form of a drum bolted to the flanged end of the shaft 42 and the mold cavities 16 are formed in the flange of the drum at radially spaced points and are preferably provided with hard metal linings 54.

The backing plate 17, is as shown in Figs. 3 and 4, shaped to conform to the inner cy-

lindrical face of the drum or carrier 15 and is of T section with its flange secured to a relatively stationary angle bracket 55 which however is mounted for movement as herein-after described along with other parts of the mechanism to withdraw the plate 17 from the interior of the carrier when desired.

The shafts 12 for the pusher members 11 carry intermeshing gears 56 and one of these shafts is oscillated to in turn move the other shaft, by its adjustable connection through a crank arm 57 on it to one end of a connecting rod 58, operatively and adjustably connected at 59 to one of a series of radially spaced pin openings 60 in a crank disk 61 on the shaft 34.

As the soap cakes C are formed in the manner heretofore described, they are intermittently moved until they reach a position here shown as opposite the mouth of the plodder and at this point they are subjected to the action of the cooperative finishing and polishing dies 62 and 63 which are secured to the heads of plungers 64 and 65 that are operated by eccentrics or cranks from the shaft 31.

Referring to Figs. 2, 4, 6 and 7, the plunger 64 has squared portions 64' slidably guided in relatively fixed guides 66 and secured by a clamping boss 67 to a block 68 to which a shaft or rod 69 is firmly secured. This shaft 69 is slidably mounted in relatively fixed bearing brackets 70 and pivotally connected by a pin 71 to the forked end 72 of a rod 73 which is mounted in guide 74 of a cap member 75 and has a headed end engaged by a spring 76 seated in said cap member, which is secured to the big end bearing or eccentric strap 77 by bolts 78, said bearing having a roller bearing journal 79 mounted on a crank or eccentric 80 formed on a part of the shaft 81. This construction thus provides a reciprocating drive movement for the die 62, the spring 76 permitting a predetermined pressure to be impressed by the die on the soap cake. The drive for the plunger 65 is similar to that just described and as shown in Figs. 2 and 4. This plunger has a squared portion 65' slidably guided in the relatively fixed guide 81 and provided with a pivot pin 82 connected to the forked end of a rod 83 which is slidably mounted in a guide 84 secured to the eccentric strap 85 and is yieldingly connected thereto by a spring 86 interposed between a flange 83' on said rod and said strap, the rod and spring being operatively held in position by a cap member 87 secured to said strap. This strap or big end bearing of the yieldable connecting rod thus formed having a journal bearing 88 mounted on another crank portion 89 of the shaft 31 to act to force the die 63 inwardly and through the spring 86 impart a predetermined pressure to the cake, the dies 62 and 63 acting conjointly under the action of their

130

springs and drive to thus compress and put the final finish on the cake before its delivery to the packaging apparatus.

The soap cake is now finished ready to 5 be discharged from the carrier 15 and conveyed by the conveyor D to the wrapping mechanism. For discharging the finished cake from the carrier a push out plunger 90 is mounted to reciprocate at the discharge 10 station G into and out of the cavity 16. Said plunger, as shown in Fig. 4 is carried by a crank arm 91 on a shaft 92 and steadied by a pivotally supported guide link 93, the shaft 92 as shown in Fig. 1, carrying a crank 15 arm 94 operatively connected to an eccentric or crank 95 on the shaft 31 by a long connecting rod 96.

In order that ready access to interior may be had at times, such as when the machine is 20 first being started, or at other times when desired, the parts have been so constructed and arranged that those working or disposed inside the carrier may be removed therefrom. For this purpose the supporting 25 bracket 55 for the plate 17 is mounted on the bearing portions 70 of a bracket 97 which carries the bearings for the plunger shafts 64, 65 and 69 and also the shaft 92 and which bracket is secured to a movable bed plate 30 98 which also carries the bearings 43⁷ for the front section of the shaft 31, said shaft being divided into sections as shown in Fig. 2 by the tooth coupling members 99 so that it may be separated at this point when the 35 bed plate 98 is moved forward. For moving the bed plate, it is provided on its bottom with suitable racks 100 meshing with spaced gears 101 on a manually operated shaft 102 journaled in the main framework 40 of the machine and provided with a hand wheel 103 and for re-aligning the parts of the coupling members 99, the other shaft section is provided with a hand wheel 104.

From the foregoing it will be noted that 45 by forming the soap directly into cakes as the soap issues from the discharge end of the plodder, I have reduced the number of operations ordinarily employed in forming the soap into cakes and that waste attendant 50 on the use of former methods has been eliminated. It is also to be noted that with the present construction the soap is expeditiously finished after being formed into the cake without any handling by an operator.

55 I desire it to be understood that this invention is not to be limited to any details of construction or other detail features except in so far as such limitations are specified in the claims.

60 What I claim as my invention is:

1. The combination with a conveyor means, of means for forming soap into cakes on said conveyor means, and means for polishing and finishing the cakes while on said conveyor 65 means.

2. The combination of a movable carrier member provided with a series of cake mold cavities, means for charging said cavities with soap, means for pressing the soap cakes to put a finish on the same while on said carrier, and means for discharging the finished cakes 70 from said carrier.

3. The combination of an intermittently movable carrier provided with a series of cake mold cavities, means for charging said cavities with soap, a pair of oppositely movable yieldingly mounted dies for engaging opposite sides of the soap cakes while on said carrier, and means for discharging the finished 75 cakes from said carrier.

4. The combination of an intermittently movable rotatable carrier having an annular flange portion provided with a series of mold cavities, means for charging said cavities with soap, a reciprocating die working inside of 80 said flange against one side of the soap cakes in said cavities, a reciprocating die disposed outside of said flange working against the opposite sides of the soap cakes, and means for discharging the finished cakes from said carrier.

5. The combination of an intermittently movable rotatable carrier having an annular flange portion provided with a series of mold 85 cavities, means for charging said cavities with soap, a reciprocating die working inside of said flange against one side of the soap cakes in said cavities, a reciprocating die disposed outside of said flange working against the opposite side of the soap cake, a movable plunger mounted within said carrier to discharge finished soap cakes from said cavities.

6. The combination of an intermittently movable rotatable carrier having an annular flange provided with a series of mold cavities, a backing plate underlying a portion of said flange, means for charging said cavities with soap, a reciprocating die working inside of 90 said flange against one side of the soap cakes in said cavities, a reciprocating die disposed outside of said flange working against the opposite side of the soap cakes, means disposed within said flange for discharging finished soap cakes from said carrier, and a movable support for said plate, the die inside 95 said flange and said discharging means for moving the same outside of said flange to provide access to the interior of said carrier.

7. The combination of a rotary carrier having a mold carrying portion and a hollow interior, finishing means within said interior acting on soap deposited in the molds in said carrier, means for intermittently rotating said carrier, means for operating said finishing means, a common drive shaft for said two last named means having separable parts, and means for moving said finishing means and its operating means and a part of said drive shaft relative to said carrier, its rotating 100

means and the other shaft to provide access to the interior of said carrier.

8. The combination with the delivery nozzle of a plodder, of oscillatory pusher member working within said nozzle, said nozzle having a curved face, a member having a portion curved to conform with said curved face and in working engagement with the same, said member having a mold cavity therein adapted to register with said delivery nozzle to receive a charge of soap therefrom, and means for moving said last named member to bring said cavity into and out of registry with said nozzle.

15 In testimony whereof, I affix my signature.
JULIUS A. SCHWANTES.
